Herman G. Pape
INVENTOR

UNITED STATES PATENT OFFICE.

HERMAN G. PAPE, OF NEW YORK, N. Y.

ACOUSTIC DIAPHRAGM.

Application filed April 15, 1928. Serial No. 102,291.

This invention relates to acoustic diaphragms and particularly to the method of deadening diaphragms and rendering them substantially non-vibratory, except under external stimuli. My invention relates further to diaphragm construction wherein a loading is provided, magnetic or otherwise, for forming a diaphragm capable only of a "dead beat".

10 In what follows the words "dead beat" refer to that manner of vibration whereby the article possessing the quality of "dead beat" vibrates only under external magnetic influence and will under conditions of practical 15 use have substantially no interfering or resonant frequency of its own. In other words, if the diaphragm having a "dead beat" is vibrated by a suddenly applied and momentary force, it vibrates only so long as the force 20 thereon continues, and ceases to vibrate when the applied force ceases. Further, a dull or "dead" sound is emitted by the diaphragm if it is struck, the sound being only momentary and setting up no sympathetic or interfering vibrations in the diaphragm. Such a 25 diaphragm is operable to produce continuous sound only under continued stimulus and can produce only the sound caused by the vibrations induced by said stimulus and no other.

30 This invention is an improvement over that shown and described in my co-pending application, Serial No. 2,358, filed January 14, 1925, for acoustic diaphragms, wherein I 35 have shown a method of adding magnetic material, preferably in a finely divided or comminuted state about the center of the diaphragm and in which I have also shown a diaphragm loaded with magnetic material 40 near the center thereof. The present invention contemplates the provision of a method whereby the most efficient magnetic loading for a diaphragm of any given thickness and for any given arrangement and shape of mag- 45 net poles for practical purposes may be pre-determined and the loading added to the central part of the diaphragm in an efficient and economical manner. The invention fur- 50 ther contemplates the provision of a dia- phragm to which a "dead beat" or a magnetic

loading, or both, is efficiently secured without detriment to the flexibility of the dia- phragm.

The various objects of my invention will be clear from the description which follows 55 and from the drawings, in which,

Fig. 1 is a top plan view of one form of my improved diaphragm showing the type of loading resulting from the use of my im- 60 proved method.

Fig. 2 is a vertical central section of the same.

Fig. 3 is a top plan view of another form of loaded diaphragm.

Fig. 4 is a vertical central section of the 65 same.

Fig. 5 is a similar view of a loading for the diaphragm in which magnetic material is eliminated, and

Fig. 6 is a top view showing one of the 70 steps of my improved method.

It is well known that if a thin diaphragm of magnetic material is arranged in the field of a sufficiently powerful magnet and particles of iron or silicon steel or other magnetic 75 material are dropped from a point above said diaphragm on to said diaphragm at points above the poles of the magnets influencing said diaphragm, the particles will arrange themselves along the shortest path of the 80 magnetic lines of force produced by the mag- net. I have discovered that if the diaphragm is then rotated about its center, even if over non-centrally arranged magnet poles, such as square faced or otherwise shaped holes, the 85 particles of magnetic material arrange them- selves in a pile or piles having a substan- tially circular base and varying in height, the height of the pile or piles being a maxi- 90 mum at the center thereof. Diaphragms loaded with such piles need not be placed in any specific position over the poles of a like magnet, any position producing the same re- 95 sults.

In order to determine the amount of mate- 95 rial and the shape of the magnetic loading to be added to the conventional diaphragm disc, I contemplate among other methods, the application of enough gummy cementitious material to the center of the diaphragm 100

as will hold together the particles of magnetic material in a pile, and as will hold said pile securely to the diaphragm. The diaphragm, if desired, being placed in the magnetic field 5 similar to those magnets with which it is to be used, said diaphragm or the magnets themselves are rotated until the particles arrange themselves in the cementitious material, which in this case is preferably gum rubber 10 dissolved in a suitable solvent. Particles are added until rotation of the diaphragm in the magnetic field causes little or no movement of said particles. The rotation may be continued until all of the particles on the diaphragm have come to rest, whereupon the rotation is stopped. It will be understood that 15 it is the relative rotation of the diaphragm and the magnets which causes the formation of the pile in its peculiar shape. The particles sink in the gum rubber until some of them have reached a point near the bottom of the 20 layer of rubber and all of said particles have been cemented together by said rubber.

I have found that when the above operation 25 is performed, above oblong or squared pole pieces as 10 and 11, there results a plurality of piles of a mixture of rubber and magnetic material consisting of a primary pile 12 having a circular base 13 at the center 30 and a secondary pile 14 in the form of an annular ring outside of the primary pile, there being left an annular space as 15 substantially free of magnetic material. I believe that the secondary ring or pile 14 is 35 formed by "eddy" lines of force radiating from the outer portions 16 of the magnets (Fig. 6).

I contemplate the prevention of the formation of the secondary pile 14, when desired, as for instance, by the application of 40 the gum rubber adhesive to a predetermined area within the range of the primary pile only, or by otherwise preventing the permanent adhesion of the magnetic particles 45 to the diaphragm at the points where the secondary pile would form. This may be done in various ways, as by covering that part of the diaphragm in a suitable manner such as by a tool or ring of the proper shape and 50 size, and then removing said tool or ring, whereby the particles that would tend to form said secondary pile are prevented from forming; or, wherewith they are removed after the secondary pile has been formed. 55 After the coat 17 of gum rubber or pile 18 of combined rubber and magnetic material has been formed, whether in the shapes shown in any of the figures, or in any other shape found to be desirable, the solvent of the gum 60 rubber is allowed to evaporate, with the result that there is left remaining a central substantially circular pile of magnetic material, or gum rubber, or both, highest at the center 19 of the primary pile. The particles, 65 if any are present, are bound together by a

flexible binder which deadens the natural frequency period of vibration of the diaphragm 20 so that the loaded diaphragm is responsive only to external magnetic influence and not to any vibration period of its own; that is, the diaphragm has a "dead beat" and may be called a "dead beat" diaphragm. Where no magnetic loading is desired, the magnetic material may be entirely omitted and the pile may be formed of gum 75 rubber only, (Fig. 5) concentrated at the center of the diaphragm or said gum rubber may be spread as an even coat over one or both sides of said diaphragm. In the latter case, the rubber coating displaces the enamel 80 ordinarily used to protect the diaphragm against corrosion. When the shape, and size of the pile have been predetermined as by the method above described, it is obvious that similar diaphragms may be loaded with similar piles as by the use of suitable well known 85 tools or depositors for depositing a predetermined amount of freely flowing material in a predetermined shape on a predetermined area in a pile of predetermined height. Such 90 tools are well known, and may be similar for instance to those used in the confectioner's art for depositing sugars, ices and cream on pastry and need not here be described in detail, as it will be understood that droppers 95 of various kinds are already in use for similar purposes, or the loading of the diaphragm may be accomplished by the preformation of piles of proper area, shape and altitude by means of suitable molds from a mixture of 100 gum rubber and finely divided particles of magnetic material. Said last-mentioned preformed piles may be secured to the diaphragm as by cementing said pile thereto by means of a thin coating of gum rubber dissolved in a 105 solvent or as may be found most practical and expedient. For instance, the pile may first be formed on a thin sheet, such as onion skin paper of extremely thin texture, and the sheet may then be cemented to the diaphragm. 110

I prefer to use gum rubber for the binder and for cementing the pile and the magnetic particles to the diaphragm for the reason that gum rubber is of such flexibility that it not only eliminates the possibility of interference with the function of the diaphragm, such as that caused by extraneous undesirable natural vibrations of the diaphragm itself not directly caused by the magnets, but because of the flexibility and resilience of that 115 material the flexibility of the diaphragm is not materially affected, even though the thickness thereof may be increased by the loading.

In order to make the magnetic loading 120 more effective, it is desirable to remove the enamel from the diaphragm at the area where the loading from the magnetic poles is made as small as possible. The gum rubber in the pile serves sufficiently as a protector, 125 130

and enamel is, therefore, not needed over the area where the rubber is present.

It will be seen that I have provided an improved method for predetermining the size and shape of a magnetic loading and for forming a diaphragm loaded with such a loading, that the diaphragm produced by said methods is a "dead beat" diaphragm, and that said diaphragm may be arranged in any position in the proper plane over the magnet poles, all positions in said plane being equally effective.

Various changes in the process and in the diaphragms shown and described are contemplated falling within the scope of the appended claims, and it is not, therefore, intended that I be limited to the specific method and construction set forth herein.

I claim:

1. The method of determining the shape and size of a diaphragm loading for a given type of magnet poles comprising dropping particles of magnetic material on said diaphragm and relatively rotating said diaphragm and said poles while said diaphragm is in the magnetic field of said poles.

2. The method of determining the shape and size of a diaphragm loading for a given type of magnet poles comprising loading said diaphragm with particles of magnetic material comparatively free to move on said diaphragm, and relatively rotating said diaphragm and said magnet poles while said diaphragm is arranged in the plane of its operative position with relation to said poles.

3. The method of predetermining the characteristics of a magnetic loading on a diaphragm comprising the arrangement of magnet poles and a diaphragm loaded with movable magnetic material in their relative operative positions, and relatively rotating said diaphragm and said poles about the axis of said diaphragm while maintaining said diaphragm in the plane of its operative position.

4. The method of predetermining the size and shape of a magnetic loading for an acoustic magnetic diaphragm in a given magnetic field comprising the relative rotation of said diaphragm and said field about the axis of said diaphragm and dropping particles of magnetic material on said diaphragm at the center thereof, while covering said diaphragm at the area where a second pile would be formed.

5. In an acoustic magnetic diaphragm, a loading comprising a pile of material, said pile being of varying height, having a substantially circular base and having its greatest height at the center thereof, said material being superimposed on and arranged at the center of said diaphragm, and including gum rubber.

6. In an acoustic magnetic diaphragm a magnetic loading comprising a substantially

conical pile of magnetic material at the center thereof and a secondary pile of less height than said primary pile concentric with and spaced from said primary pile.

7. In an acoustic diaphragm, a magnetic loading comprising a plurality of concentric piles of finely divided magnetic material superimposed on the diaphragm.

8. In an acoustic diaphragm, a plurality of piles of finely divided magnetic material arranged concentrically about and superimposed on the center of said diaphragm and a gum rubber binder for said piles securing said piles to said diaphragm and securing said particles in said piles.

9. In an acoustic diaphragm, a centrally arranged pile having a circular base, a height greatest at the center and least at said base, particles of magnetic material and gum rubber in said pile, and a second annular pile including the same material as said central pile, of less height than and arranged concentrically with and in spaced relation to said central pile.

10. In an acoustic diaphragm, a magnetic loading superimposed on the diaphragm comprising finely divided magnetic particles arranged substantially in the form of a cone with the top of said cone rounded and a gum rubber binder for said particles.

11. The method of forming loadings for diaphragms comprising the predetermination of the characteristics of the loading for a given magnetic field by rotating a diaphragm in said field about the axis of said diaphragm and dropping finely divided particles of magnetic material on said diaphragm near the center thereof, forming piles of a mixture of magnetic material and dissolved gum rubber, having the same characteristics as the pile so predetermined, and securing said piles to the central portion of diaphragms.

12. In connection with a loaded magnetic diaphragm constituting an actuated means and a given type of magnet poles constituting an actuating means, the method of determining the shape and size of a loading for said actuated means for use with a given type of actuating means comprising the loading of said actuated means with particles of magnetic material comparatively free to move on said actuated means, while in operative relation to said actuating means, and rotating at least one of said means.

13. In connection with a magnetic diaphragm constituting an actuated member and an electrically operated actuating member the method of predetermining the characteristics of a magnetic loading for such an actuated member comprising the arrangement of said actuating and actuated members in their operative relation, loading said actuated member with movable magnetic material, and rotating one of said members while maintaining the operative relation of said members.

14. In connection with an acoustic diaphragm constituting an actuated member the method of predetermining the size and shape of a magnetic loading for such an actuated member in the field of a magnet constituting an actuating member, comprising rotating one of said members about its axis while particles of magnetic material are concentrated in a pile at the central portion of said actuated member and covering said actuated member to prevent the formation of a secondary pile on said actuated member.
